SHEARING DIES FOR SPRING PLATES.

1,426,470.

Specification of Letters Patent. Patented Aug. 22, 1922.

Application filed March 29, 1921. Serial No. 456,567.

To all whom it may concern:

Be it known that I, JAMES A. FRAY, citizen of the United States, residing at Bridgeport, in the county of Fairfield and State of Connecticut, have invented certain new and useful Improvements in Shearing Dies for Spring Plates; and I do hereby declare the following to be a full, clear, and exact description of the invention, such as will enable others skilled in the art to which it appertains, to make and use the same.

This invention relates to shearing dies adapted for shearing spring plates, and it consists in so shaping the dies that two ends 15 are simultaneously sheared from the body of a metal strip and the ends separated without loss of stock.

Referring to the accompanying drawings; Figures 1 and 2 represent inside views of 20 the dies;

Figure 3 is a side elevation of the dies in operative position with a broken view of a metal strip resting on the lower half of the die;

25 Figure 4 is a front elevation of the dies in operative position, minus the metal strip, looking in the direction of arrow *a*, Figure 3;

Figure 5 is a view of the lower die showing the effect of the shearing, broken view of the metal strip and finished spring plate;

Figure 6 is a central section of the lower die on line 6-6 of Figure 1, showing the finished spring plate severed from the metal 35 strip and the end of the metal strip sheared, and

Figure 7 is a broken view of the metal strip and finished spring plate after the separation of the latter from the former.

40 The two parts of the complete die, shown in Figures 1 and 2, are provided with the base 1 and 2 adapted to be connected with a power press or other well known machine adapted for operating the dies.

45 While the two parts of the complete die are exactly alike, they will be designated by different figures and letters of reference in order to bring out more clearly their workable relation. 3 and 4, Figure 1, are 50 tapered punch-like projections having the shearing edges *b*, *e*, *d*, *e*, *f*, *g*, while the projections 5, 6, have the shearing edges *h*, *i*, *j*, *k*, *l*, *m*, *n*, *o*.

When the two parts of the die are assembled in operative position, the shearing

edges *h*, *i*, Figure 2, will register with the shearing edges *b*, *c*, Figure 1, and the shearing edges *j*, *k*, with the edges *o*, *n*, and the edges *e*, *f*, with the edges *l*, *m*, and the shearing edge *d* with the edge *g*.

In operating the die in a common power press, one half will necessarily be stationary and the other movable, and as both parts are alike it is immaterial as to which is used as the upper or movable half, or the lower or stationary half. Whichever half is used as the lower or stationary member, one solid punch member 3 or 4 is preferably located at the work entrance of the die to form a support for a metal strip, in Figures 3, 4, 5, and 6, the punch member 3 being so located.

In shearing the ends and cutting of spring plates to any desired length, the end of the metal strip 7 is placed upon the solid member and its end pointed by the die, then the strip is advanced, Figure 5, and the waste pieces 8, 9, 10, and 11, are sheared off to form the tapered end 12 on the end of the metal strip 7, and the tapered end 13 on the finished spring plate 14. The tapered end 15 of the spring plate having been previously sheared as before mentioned. At the same time that the end 13 of the spring plate and the end 12 of the metal strip are pointed, the spring plate 14 is severed from the metal strip on the line *p* by the shearing edges *d* and *g* of the punches, Figures 1 and 2. As soon as the finished spring plate is severed, it will drop into the recess 16, Figure 6, located between the shearing edges *l*, *m*, Figures 1 and 6, or into the recess 17, Figures 2, 3, and 4, when the two parts of the die are reversed from the position shown in Figures 3 to 6 inclusive. Severing the finished plate from the metal strip on the line *p* is thus done without a particle of waste, and the only waste are the side pieces 8, 9, 10, and 11.

Having thus described my invention what I claim is:

1. In a shearing die, an upper and a lower die each a counterpart of the other, each die having an inwardly tapered punch and each having transverse cutting edges at their inner ends, said dies each having inwardly tapered shearing recesses for receiving the respective punches of the complementary die, said transverse cutting edges being substantially in register with each other so as

to cut the stock on a single transverse line which latter forms an end of each of the severed parts of the stock.

2. In a shearing die, an upper and a lower die, each die having a male and a female part, the male part of each die being received in the respective female part of the other die, each die having transverse shear-

ing edges located at the inner edges thereof which edges are in approximate register so as to cut the stock on a single transverse line which latter forms an end of each of the severed parts of the stock.

In testimony whereof I affix my signature.

JAMES A. FRAY.
